CLAIM

The ornamental design for a combined storage and display assembly, as shown and described.

DESCRIPTION

FIG. 1 is a perspective view of a combined storage and display assembly showing my new design;

FIG. 2 is a front elevational view thereof;

FIG. 3 is a right side elevational view thereof; the left side elevational view being a mirror image thereof;

FIG. 4 is a top plan view thereof; the bottom plan view being a mirror image thereof;

FIG. 5 is a rear elevational view thereof;

FIG. 6 is a perspective view of a first alternative embodiment thereof;

FIG. 7 is a front elevational view thereof;

FIG. 8 is a right side elevational view thereof; the left side elevational view being a mirror image thereof;

FIG. 9 is a top plan view thereof; the bottom plan view being a mirror image thereof;

FIG. 10 is a rear elevational view thereof;

FIG. 11 is a perspective view of a second alternative embodiment thereof;

FIG. 12 is a front elevational view thereof;

FIG. 13 is a right side elevational view thereof; the left side elevational view being a mirror image thereof;

FIG. 14 is a top plan view thereof; the bottom plan view being a mirror image thereof; and,

FIG. 15 is a rear elevational view thereof.

The dotted line showings in FIGS. 1, 6 and 11 are for environmental purposes only and form no part of the claimed invention.
